(Model.)

T. R. ELLERBECK & A. C. YOUNG.

HOSE AND ROPE REEL.

No. 286,408.

Patented Oct. 9, 1883.

UNITED STATES PATENT OFFICE.

THOMAS R. ELLERBECK AND ALBERT C. YOUNG, OF SALT LAKE CITY,
UTAH TERRITORY.

HOSE AND ROPE REEL.

SPECIFICATION forming part of Letters Patent No. 286,408, dated October 9, 1883.

Application filed July 10, 1883. (Model.)

To all whom it may concern:

Be it known that we, THOMAS R. ELLERBECK and ALBERT C. YOUNG, both of Salt Lake City, in the county of Salt Lake and Territory of Utah, have invented a new and Improved Hose and Rope Reel, of which the following is a full, clear, and exact description.

The object of our invention is to provide a new and improved reel for hose, rope, &c., in which the hose or rope is wound automatically.

The invention consists in a hose or rope reel containing a spring which is coiled by the unwinding of the rope or hose, which spring winds up the hose or rope as soon as it is released. To prevent overwinding of this spring or unwinding it too far, we have arranged the drum to travel on its axis and strike against checks, after making sufficient revolutions to tighten the spring as much as may be necessary.

Reference is to be had to the accompanying drawings, forming part of this specification, in which similar letters of reference indicate corresponding parts in all the figures.

Figure 1 is a longitudinal sectional elevation of our improved hose and rope reel. Fig. 2 is a plan view of the same. Fig. 3 is a cross-sectional elevation of the same on the line *xx*, 30 Fig. 1.

A shaft, A, is fixed between two side bars, B, of a hose-carriage or other suitable frame. One end of the shaft is left plain and the other end is screw-threaded.

A drum or reel, C, the length of which is less than the distance between the bars B, is loosely mounted on the shaft A, the edge of the aperture in one end piece being screw-threaded, so as to engage with the screw-thread on the shaft A, thereby causing the drum to travel longitudinally on the shaft at the same time while revolving. The shaft A is provided with a check-collar, D, to limit the movement of the drum on the shaft in the direction of the length of the latter.

A coil-spring, E, wound around the shaft A, has one end secured to the said shaft, and the other end is held loosely on a rod, F, uniting the end pieces of the reel near the edges of the

same. The spring E is held between two plates, 50 G, mounted loosely on the axle and connected with the reel or drum.

The end pieces of the drum are provided with handle-pieces H for holding the hose or rope in position on the drum. A ratchet-wheel, 55 J, loosely mounted on the shaft A, is provided with two pintles, K, which pass loosely through one of the end pieces of the drum, so that if the drum is revolved the ratchet-wheel J will revolve with it. A pawl, L, pivoted to one 60 of the side bars, B, has its free end pressed against the teeth of the ratchet-wheel by a spiral spring, M, surrounding a rod, N, provided with a handle-piece, O, at one end and fastened to the pawl at the opposite end. The 65 spring M is held between the pawl and a guide-loop, P, on the side bar, B.

The operation is as follows: The reel is first wound by hand until the spring is tightened. Then the hose is attached to the reel, which is 70 released, whereby the hose is wound on it. The hose is then coupled to the hydrant, and the hose-cart is drawn to the desired place, and the nozzle Q of the hose is removed from the reel or drum, and is used to sprinkle or 75 deliver a stream, &c. By unwinding the hose, which is done if one end of the hose is fastened and the reel is drawn from the hydrant to which the hose is coupled, the reel or drum will be turned in such a manner as to wind up or 80 coil the spring E tightly. At the same time the reel travels in the direction toward the ratchet-wheel, and one end piece strikes the end of the thread or the ratchet-wheel, and this stops 85 the revolving movement of the reel and prevents overwinding of the spring. If the hose is to be wound on the reel or drum, the nozzle end of the hose is held on the reel by one of the clamps provided for this purpose, the spring-pawl L is withdrawn from the ratchet-wheel, and is held in this position by passing the handle-ring O over a pintle, S, projecting 90 from the inner surface of one of the side bars, B. The cart is then pushed back to the hydrant to which the other end of the hose is fastened, and as the spring E uncoils it winds the hose on the reel nicely, evenly, and rapidly. This carries the drum back to the collar 95

D, and prevents unwinding the spring too far, thereby preventing any breakage of the spring.

The above-described reel can be used for ropes, &c., as well as for hose, and can be used 5 for the smallest garden-hose and the largest fire-hose.

We do not abandon or dedicate to the public any patentable feature set forth herein and not hereinafter claimed, but reserve the right 10 to claim the same, either in a reissue of any patent that may be granted upon this application, or in other applications for Letters Patent that we may make.

Having thus described our invention, what 15 we claim as new, and desire to secure by Letters Patent, is—

1. A reel provided with a spring which is wound or coiled by unwinding the hose or rope 20 from the reel, which reel is adapted to travel longitudinally on its shaft, substantially as herein shown and described.

2. In a reel, the combination, with a shaft having one end screw-threaded, of a drum 25 mounted loosely on the said shaft and engaging with the screw-thread, and of a spring connected with the shaft and drum, and adapted to be coiled while the rope or hose is being unwound from the drum, substantially as herein shown and described.

3. In a reel, the combination, with the shaft A, having one end screw-threaded, of the 30 drum C, the collar D, and the spring E, substantially as herein shown and described.

4. In a reel, the combination, with the shaft A, having one end screw-threaded, of the 35

drum C, the collar D, the spring E, the plates G, and the rod F, substantially as herein shown and described.

5. In a reel, the combination, with a shaft, 40 of a drum mounted loosely and adapted to travel longitudinally on the same, a ratchet-wheel loosely mounted on the drum, and of pintles or rods projecting from the ratchet-wheel into one end of the drum, substantially as herein shown and described.

6. In a reel, the combination, with the shaft A, of the drum C on the same, the spring E, the ratchet-wheel J, the pintles K, extending 45 from the ratchet-wheel through one end of the drum, a pawl, L, and a rod, N, for withdrawing it, substantially as herein shown and described.

7. In a reel, the combination, with the shaft A, of the drum C on the same, the spring E, the ratchet-wheel J, the pawl K, the rod N, 50 and the spring M, substantially as herein shown and described.

8. In a reel, the combination, with the shaft A, of the drum C on the same, the spring E, the ratchet-wheel K, the pawl L, the rod N, 55 the spring M, the handle-loop O, and the stud S, substantially as herein shown and described.

THOMAS R. ELLERBECK.
ALBERT C. YOUNG.
